UNITED STATES PATENT OFFICE

2,541,431

WATCHCASE WRENCH

Carl Muehlbauer, Flensburg, Minn.

Application May 28, 1947, Serial No. 750,929

1 Claim. (Cl. 81—6)

1

The present invention relates to new and useful improvements in watch case tools and more particularly to tools of this character adapted for removing screw-type backs of watch cases.

An important object of the present invention is to provide a watch case tool to facilitate the removal of screw-type backs on watch cases that have become tightly sealed or corroded and without requiring the use of a special jig to hold the watch case.

A further object of the invention is to provide a tool of this character comprising a pair of pivoted jaws, one of which is constructed to enter a notch in the peripheral edge of a screw-type watch case while the other jaw is held in gripping engagement with the side edge of the case in a position to exert a rotary movement on the back of the watch case by a closing action of the jaws and to provide a protective cover for the jaw which engages the side of the watch case to prevent marring or injury to the finish thereof.

A still further object of the invention is to provide a watch case tool constructed in the form of a pair of pliers and in which the ends of the jaws are adapted to enter notches or recesses at the diametrically opposite side edges of the back of a watch case and by a rotation of the tool about its longitudinal axis to apply or remove the back of the watch case.

Another object is to provide a tool of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a plan view of the back of a watch case showing the jaws of the tool in section and engaged in the notches of the back of the watch case.

Figure 3 is a similar view showing the jaws in section and arranged to function as a pair of pliers to loosen a tightly fitted or corroded back of the watch case.

Figure 4 is an enlarged sectional view taken on a line 4—4 of Figure 1.

Figure 5 is a fragmentary side elevational view of the jaws with part of the guard broken away and shown in section, and

2

Figure 6 is an enlarged fragmentary perspective view of the inner jaw.

Referring now to the drawing in detail, wherein for the purpose of illustration I have disclosed a preferred embodiment of the invention, the numeral 5 designates the watch tool generally, which is constructed in the form of a pair of pliers and including handles 6 and 7 pivoted to each other in crossed relation by a pin 8 in a conventional manner.

The handle 6 at its outer end is formed with an outer jaw 9 of relatively narrow transverse width and formed with a substantially straight face 10 disposed at right angles to the outer end portion of the handle 6.

An inner jaw 11 is formed at the outer end of the handle 7 and the pivot pin 8 is adjustable longitudinally in a notched slot 12 in the handle 6 to adjust the jaws relative to each other in a conventional manner.

The inner jaw 11 is likewise substantially narrow transversely and is formed with a straight inner jaw face 13 and a transversely rounded outer jaw face 14, the back of the jaw 11 at its outer edge being rounded as shown at 15 to provide a substantially tapering extremity 16 at the outer end of the jaw.

The tool is designed particularly for use in removing the screw-type back 17 of a watch case 18 and in which the back is formed with radially extending slots or notches 19 at its peripheral edge.

To facilitate removal of the back, the outer ends of the jaws 9 and 11 are inserted in a pair of the notches 19 at a diametrically opposite side of the back 17 as shown in Figure 2 of the drawings, and by rotating the tool about its longitudinal axis, the back of the watch case may be easily removed or tightened.

When the back of the watch case is particularly tight or corroded, the tool is used as a pair of pliers by inserting the end 16 of the inner jaw 11 in one of the notches 19 and engaging the outer jaw 9 with a side edge of the watch case 18, as shown in Figure 3 and by closing the jaws to exert pressure on the back in a substantially tangential direction the back will be broken loose from the case.

When used in this manner, a protector or guard 20 of relatively soft metal or other material of channel-shape construction in cross-section and closed at each end is frictionally fitted on the jaw face 10 of the outer jaw 9 to prevent marring or scratching of the edge of the watch case. The inner edge of the jaw face 10 is formed with a

notch 21 to receive the inner closed end 22 of the guard to hold the guard on the jaw.

The rounded outer end 14 of the inner jaw 11 facilitates the entry thereof into the notches 19.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention what is claimed as new is:

A tool for removing and applying a threadedly attached back on a watch case, and comprising a pair of pivotally connected handles and jaws on the handles, one of said jaws engaging the side of a watch case and the other of said jaws en-

gaging the back of the case to rotate the back upon a closing movement of the jaws, and a channel-shaped protective cover frictionally mounted on the work-engaging face of said first named jaw, said cover having its ends closed and said first named jaw having a notch at the inner end of its work-engaging face receiving the closed inner end of the cover.

CARL MUEHLBAUER.
